United States Patent Office

Des. 176,618
Patented Jan. 10, 1956

176,618

CHAIR

William J. Kranz, Cuba, N. Y., assignor to Viko Furniture Corporation, Eldred, Pa., a corporation of Pennsylvania

Application December 9, 1953, Serial No. 27,992

Term of patent 7 years

(Cl. D15—1)

Fig. 1.

Fig. 2

Fig. 3

Fig. 1 is a perspective view of a chair showing my new design;

Fig. 2 is a top plan view of the structure shown in Fig. 1; and

Fig. 3 is a rear elevational view.

I claim:

The ornamental design for a chair, substantially as shown.
